METHOD FOR GRINDING GYRATORY CRUSHER WEARING PARTS

Willard C. Jackson, Milwaukee, and Walter E. Ruehmer, South Milwaukee, Wis., assignors to Nordberg Manufacturing Company, Milwaukee, Wis., a corporation of Wisconsin

Filed Apr. 2, 1957, Ser. No. 650,134

1 Claim. (Cl. 51—281)

This invention is in the field of grinding wearing parts, such as mantles and liners, for use on or with gyratory crushers and the like, although many of the characteristics, features and aspects of the invention are not necessarily restricted thereto. In any event, the invention is concerned with a method and apparatus for grinding a rough casting of manganese steel or the like to produce a finished frusto-conic wearing element for use on a gyratory crusher.

A primary object of our invention is a method of grinding generally frusto-conic manganese steel castings.

Another object is a method of grinding castings of the above type to insure concentricity of the fit and wear surfaces.

Another object is a method of grinding a mantle to insure a proper nut seat at the small end.

Another object is a machine for grinding liners or mantles, or both, to insure concentricity on the finished product.

Another object is a method of preliminarily assembling or prechucking the frusto-conic manganese steel castings to reduce down time in a grinding machine.

Another object is a machine for grinding the fit and wear surfaces of both mantles and liners simultaneously.

Another object is an improved manganese steel frusto-conic wearing part for use on gyratory crushers and the like.

Another object is a frusto-conic manganese steel mantle constructed to insure a smooth concentric nut seat.

Another object is a method for automatically and simultaneously grinding the wear and fit surfaces on a mantle or liner to insure concentricity in the finished article.

Other objects will appear from time to time in the ensuing specification and drawings in which:

Figure 1 is a perspective of a grinding machine with a mantle in position being ground;

Figure 2 is an enlarged perspective of the right hand grinding spindle in Figure 1 showing the control mechanism;

Figure 3 is an axial section through the grinding zone with a bowl liner being ground and showing, diagrammatically, the grinding heads in operation;

Figure 4 is a view similar to Figure 3 but of a modified form;

Figure 5 is a top plan view of a prechucking structure usable with the machine of Figure 1; and

Figure 6 is a side view of Figure 5.

In Figure 1, the basic machine is shown. It may include a suitable base, indicated generally at 10, rotatably supporting a generally upright table 12 or the like defining a grinding zone, indicated generally at 14. On each side of the table and grinding zone are uprights or posts 16 and 18 which support a generally horizontal crossrail 20 or the like. The crossrail is adapted to be moved up and down the posts and is mounted so that it stays generally horizontal. The superstructure or bridge 22 across the top of the uprights or posts is stationary

and serves as a support for suitable power mechanisms, hydraulic circuits, electric drives, control circuits, and the like, none of which is important to this invention.

The table may be rotated by any suitable conventional driving mechanism, not shown, which may provide for a full range of speeds. Through a suitable power mechanism, not shown in detail, the crossrail may be raised and lowered. For example, a gear box 24 or the like at the foot of upright 16 is connected by suitable lead screws 28 and the like to the mechanism of the crossrail. A similar gear box 30 and lead screws 32 are provided adjacent the other upright 18. The details of this mechanism, in and of themselves, may be conventional.

We provide two saddles 34 and 36 on the crossrail, 15 one on each side of the grinding zone and table. The crossrail may carry a suitable power mechanism and a drive so that the saddles, either together or independently, may be moved back and forth along the crossrail. For example, note the lead screw 38. In any event, the important point is that the saddles move along suitable ways on the crossrail to provide for a desired adjustment. Each saddle carries a spindle mechanism, for example, at 40 and 42. Each such spindle has a grinding head at its lower end, for example, at 44 and 46. The spindles 25 project toward the grinding zone and the grinding heads might be characterized as residing at or in the grinding zone. Each spindle is mounted on a somewhat large gear, as at 48 and 50, each of which is pivoted to its saddle, as at 52 and 54. Note that each spindle is eccentric to the pivot for the gear that carries it.

Rotation of the gears 48 and 50 about their respective pivots will cause the spindles to be rotated bodily about the pivots 52 and 54, thereby providing an adjustment for the direction at which each of the grinding heads 35 approach or project into the grinding zone. The gears may be suitably rotated by a worm-drive, as at 56 and 58, which may be driven by any suitable power mechanism, not shown in detail because, as such, it is not important in detail to this invention. The front of the crossrail may be provided with suitable covers 60, if desired. Between the uprights or posts we may provide an arcuate shield 62, if desired, behind the grinding zone, to prevent the coolant from being splattered or otherwise thrown onto adjacent equipment. The floor or base 40 of the unit may be a grill, or screen type arrangement, so that the coolant, used in the grinding operation, may flow off of the rotary table 12, through the screens to a suitable sump or collecting zone for recirculation.

In a conventional manner, the upper surfaces of the 50 table may be provided with a plurality of radially disposed T-slots 64 adapted to receive bolts or other suitable connecting elements to fasten clamps, jaws, or other suitable supporting mechanism, indicated broadly at 66, to the table. The workpiece 68, shown in Figure 1, 55 generally represents a manganese steel frusto-conic mantle for use on the head of a gyratory crusher. For example see U.S. Patent No. 2,684,208. As shown, the mantle is mounted on jaws on the rotary table with its large end up.

In Figure 4 which shows a variant form of machine and method, we have the same or a similar type of mantle, in section. Such a mantle has an inner frusto-conic fit surface 70 adjacent or at the large end and a frusto-conic wear surface 72 on the outer surface which 65 coacts with the material being fed into the crushing cavity of a gyratory crusher between the gyrating head and the bowl. Note also that the wear surface 72 may be generally adjacent but spaced from the end or edge at the large end of the mantle by a down turned portion or lip 74, but it might be otherwise.

We have indicated the same fit surface and wear surface 70 and 72 on the mantle in Figure 1. As shown, the

mantle is supported by the fixtures or jaws, 66, which engage its outer surface generally adjacent the small end and a suitable centrally disposed pulldown mechanism may project up through the open small end of the mantle and clamp against the inner surface in any suitable manner, not shown. As for the clamping and supporting mechanism to hold the mantle rigid during a grinding operation, suffice it to say that any suitable fixtures or jaws or clamps may be used, either supported or attached directly to the upper surface of the table, as shown in Figure 1, or in accordance with the variant form of Figure 5 to be explained hereinbelow.

A bowl liner is shown in Figure 3, generally at 76. Such a liner is similar to a mantle in that it has a generally frusto-conic body portion which is disposed big end up on the table. But its wear surface is on the inner surface of the frusto-conic body, as at 78, and its fit surface is on the outer surface, as at 80. This is the reverse of the mantle. But they are similar in that each has a fit and a wear surface. In each case, one such surface is on the inside of the casting, adjacent the large end, and the other is on the outside, also adjacent the large end. The bowl liner in Figure 3 is suitably supported by jaws or clamps and suitable hooks 82 or the like connected to the table by bolts 84 or the like may be used to pull down the mounting hooks 86 which are normally found on bowl liners and are used to mount the bowl liner on the bowl of a gyratory crusher.

In general, the mantle and liner, explained somewhat in detail hereinabove, are representative of the type of wearing parts used in gyratory crushers with which we are concerned in this invention. While the broad aspect of the invention may be applied to either, there are certain specific aspects, set forth in detail hereinbelow, which may be considered restricted to one or the other.

In general, the wearing part or element, whether a mantle or liner, is a frusto-conically shaped manganese steel rough casting. Such castings are notoriously out of round, and before they can be applied and used on gyratory crushers, the fit and wear surfaces must be trued. This has previously been done by either machining or grinding. Machining is too expensive and too slow, and, more important, manganese steel has very poor machining properties. In fact, for many uses it is widely accepted as a nonmachinable material. While grinding has been used, it too has proved expensive and, more important, inaccurate. For example, in the finished product, there must be a matched concentricity between the wear and fit surfaces. Prior grinding processes have failed to obtain this. Also, grinding processes have been generally time consuming and, therefore, additionally expensive. Further, such grinding processes are quite slow, require the use of a number of machines to perform different steps, tie up an excessive amount of capital equipment and floor space for the small amount of finished wearing elements produced.

One of the important aspects of our invention is that we simultaneously grind both the wear and the fit surfaces. The table supporting the casting to be ground is rotated at a generally uniform rate of speed. The grinding heads are automatically and uniformly moved back and forth in the grinding zone across the surfaces and grinding is done simultaneously to insure concentricity of these two surfaces on the finished piece. For example, in Figure 3 the grinding head 44 is indicated to reciprocate back and forth across the wear surface 78. At the same time, the grinding head 46 is indicated as reciprocating back and forth across the fit surface 80. In the finished piece, these two surfaces will have been ground simultaneously and their concentricity will be exact.

As for the details, in Figure 1, each spindle may include a cylinder or housing, as at 88 and 90, which carries a quill or plunger 92 and 94 or the like. Through a suitable actuating mechanism, not shown in detail, each

of the plunger mechanisms may be caused to move back and forth within their cylindrical housings. For example, a rack may be secured on the plunger or piston driven by a suitable pinion which in turn could be driven by any suitable power mechanism, hydraulic, electric, or otherwise, contained in or mounted on the cylinder housing. For example, note the rack 96 on the plunger or piston 94. Or a piston and cylinder may be secured to the quill. The important point is that each of the plungers or pistons is caused to reciprocate back and forth within its housing or mounting so that the grinding head carried at the end may be caused to move back and forth across the surface on the casting to be ground. The distance moved by the grinding head during this reciprocation shall be referred to as the grinding stroke or stroke.

To regulate and effectively control the length of this stroke, we provide a control mechanism. For example, the control mechanism may include upper and lower brackets or mountings 98 and 100, in Figure 1, each of which is mounted to move with the quill or piston. Between the supports or brackets, we extend two rods 102 and 104 which may be adjustably mounted on the supports or brackets. These rods extend generally parallel to the piston and move with it. We shall only refer to the control mechanism on the right-hand grinding unit and spindle, designated generally 42 in Figure 1, but the same structure may be applied to the left-hand unit. In detail in Figure 2, the cylinder or support 90 may carry a suitable bracket 106 which in detail is unimportant. This bracket or support carries two sets of microswitches or the like, one set being designated 108 opposite the rod 102 and the other set being designated generally 110 opposite the rod 104. Each microswitch of the set may include a lever 112 with a roller on the end or otherwise and the rods carry suitable cam elements, adjustably mounted. For example, the rod 102 has lower and upper cam elements 114 and 116 while the rod 104 carries suitable lower and upper cam elements 118 and 120. Either rod may be considered the primary or controlling rod while the other functions as a safety. For example, the rod 102 may perform the actual reciprocal control with the rod 104 being the safety. In this case, the stops 114 and 116 are adapted to engage the levers on the microswitches of the set 108 in response to movement of the plunger or piston. The cams kick the switches back and forth. The switches may be suitably connected, as by the leads shown in Figure 2, to a suitable conventional reversing mechanism so that the power to the piston may be reversed whenever either one of the cams trip the switches. The cams on the safety rod 104 are merely safety cams so that in the event the normal reversing mechanism is faulty and either of the normal controlling cams 114 and 116 pass through the switches 108 without effect, the cams 118 and 120 on the safety rod will hit their auxiliary switches 110 to reverse the plunger and prevent the grinding head from moving too far in either direction and cause damage. For example, the safety cams 118 and 120 might be set to prevent the grinding head 46 in Figure 3 from reaching the hooks 86 on the bowl liner in the event that the normal cams malfunction.

The important point is that the cams 114 and 116 are set to define the stroke of the grinding head. This is true of both heads. The power mechanism moves the grinding head at a predetermined linear velocity, relative to the speed of rotation of the table 12 and also the peripheral speed of the surface being ground on the casting, so that a predetermined thickness of material at the surface of the casting will be rough ground and removed. The stops or cams will normally be set so that the grinding head just clears the surface undergoing grinding at each end when reversing takes place, but not necessarily.

The details of the power mechanism, the reversing mechanism, and the control mechanism are unimportant.

to our invention, and accordingly we have not shown them.

The casting undergoing grinding is positioned on the rotary table in the grinding or working zone with its axis generally upright and concentric with the rotary axis of the table. For example, such axis is indicated generally at X in Figure 3. The casting is rotated about this axis. The grinding heads are brought in from opposite sides, on one side the grinding head moves into the casting, such as the head 44 in Figure 3, and grinds the inner surface, in this case the wear surface of a bowl liner. The other head moves somewhat below the casting and across the outer surface, in the case of Figure 3, the fit surface of the liner. In each case the grinding head is reciprocated through a predetermined grinding stroke. The stroke of each head is determined automatically by a mechanism, such as in Figure 2. The stroke of the two heads may be different, depending upon the width of the ground surfaces desired. In any event, one head, for example the head 44, reciprocates back and forth along its axis Y while the other head reciprocates back and forth along its axis Z, these axes being understood to be the centerlines, or generally so, of the spindle units. These axes intersect the X axis of the workpiece, but not at the same point, which is clearly shown in Figure 3. In other words, the direction of movement of either head during its reciprocation would, if extended, intersect the rotary axis of the piece and table. Further, the three axes, X, Y and Z, are coplanar and their plane would be upright, perpendicular to the base and would generally pass laterally across the front of the machine through the middle of the grinding zone, such as in Figure 1.

In addition to having a certain reciprocating stroke, each head also has a feed, and this feed is acquired by an automatic movement of the saddle horizontally along the rail. For example, at a predetermined time, the saddle 34 in Figure 1 moves a predetermined amount to the left. The same is true of saddle 36, namely, to the left. In each case the grinding head carried on the spindle of that saddle will be fed into the work. The amount of feed is a combination of the desired amount of material to be removed from the casting, as well as a compensation for wheel wear, and may be varied to suit conditions. Whatever the feed is, the saddle might be moved this amount once during each reciprocation cycle of the plunger or piston and grinding head.

We prefer that a certain amount of feed be applied to the saddle of each head at each end of its reciprocation, and this may be easily attained. For example, consider the set of microswitches 108. One switch of the set could be used as the reverse switch to reciprocate the plunger and grinding head back and forth while the other switch could be used to automatically feed the saddle a predetermined amount. In this manner, when the grinding head was at either the top or the bottom of its stroke, it would be fed a certain distance toward the work. The stops or cams 114 and 116 are set to the limits of the stroke, which determines the point of lateral feed, and the microswitches are electrically connected to the feed mechanism so that the feed may be applied at the top or bottom of the stroke or at both or at either. A manual control button is included on the control panel, described later, to permit the feed mechanism to be actuated at any desired point between the top and bottom of the stroke.

Also, the coolant is important and we have shown coolant connections 122 and 124 in Figure 1, but the details are otherwise unimportant and may be conventional. The grinding heads need not reciprocate together or in unison but they do reciprocate at the same time. Their speeds, strokes, peripheral speeds, and other characteristics may be different. But we do prefer that they operate simultaneously so that the inner and outer ground surfaces will be accurate in concentricity. By grinding simultaneously, each ground surface is concentric about

the axis of rotation X which is the general axis of the casting.

In use, we provide a generally upright pivoted post 126 mounted on and projecting above the top 22 of the machine or otherwise, which has a boom 128 and suitable depending cables or leads 130 to a control board or panel 132, which is at waist or chest level or otherwise for use by the operator. The panel has a plurality of control buttons and the operator in starting, stopping, and otherwise handling the machine, may pivot the control panel from one side to the other of the rotary table and grinding zone so that he can, at all times, simultaneously observe and control the operations of any of the moving parts. For example, we prefer that the controls on the panel be such that the operator may manually feed the saddles in or out, independently or together, raise or lower the crossrail, start and stop the grinding heads, and pivot the spindles about their pivot points on the saddles. Also, the operator should be able to start and stop the table, as well as other things.

In starting a grinding operation, the operator moves the grinding heads in toward the grinding zone by bringing the saddles inwardly. Previously, the casting, be it a mantle or a liner, would have been positioned properly on the table. The angle of the spindles should then be adjusted so that the heads, during their reciprocation, will move generally parallel to the surfaces to be ground. The operator should then raise the head 44 above the casting by retracting it and bring it over the casting by feeding the saddle 34 inwardly. The head should then be lowered until it projects down into the casting slightly and the stops should be set roughly to determine the extent of reciprocation during the working stroke. With this roughly set, the operator would then move the saddle to the left bringing the head 44 toward the inner surface, in Figure 3 this being the working surface. As soon as the grinding head made contact, manual lateral feed of the saddle should be stopped and the other grinding head 46 should be set in a similar manner. But in the case of the outside grinding head, as compared to the inside head, it would not have to be lowered into the casting from above. Rather, it could come straight into the side until it contacted the surface to be ground. With each of the heads taking a bite out of its respective surface, the stops would then be accurately positioned, the amount of feed would be determined and sent into the unit, and the machine would be thrown into "automatic." Each head would take up its reciprocation and its automatic feed, each feeding to the left, as in Figure 3, the feed being effected at the top and bottom of each stroke. The operator would then be through until grinding was completed.

It might happen that one grinding head would finish its surface before the other, in which case the operator could easily throw that head back on to manual and move it out of contact with the casting, allowing the other head to complete grinding on "automatic." If the castings are all of the same general size and dimensions, the machine could be set up with a fixed stroke, feed and speed and the operator would merely have to manually bring each head into contact with the work and then put the machine on "automatic." But this would vary from one unit to another.

One of the important points of the Figure 1 arrangement is that each spindle is on the same side of its pivot. For example, note that the spindle 40 is on the righthand side and generally above its pivot 52. The spindle 42 is also on the righthand side but generally below its pivot 54. This is important because the head 44 of the spindle 40 works down and in the casting, while the head 46 works under and up to the casting, more or less. If the spindles were symmetrically arranged, relative to their pivot, either both inside or both outside, the rail would have to be impossibly long because one of the spindles would not be able to reach its work point conveniently.

For example, if the spindle 42 was above its pivot 54, to reach the working surface 72 with the head 46, the saddle 36 would have to be moved farther to the right in Figure 1 and the spindle and rail would have to be extended so that the head could reach the casting. The machine would be cumbersome, unnecessarily expensive and require additional floor space and heavier parts. By the arrangement shown, the rail may remain short and the spindles do not have to be excessively long.

In Figure 4, we have shown a variation in which the rail is indicated generally at 20', the saddles at 34' and 36', and the left and right spindles at 40' and 42'. The mechanism may be generally the same as in Figure 1. As set forth hereinbefore, the workpiece is a mantle. In this case, we provide an auxiliary or third or inside spindle which includes a saddle 134 mounted on the rail to be moved back and forth and a generally vertical or upright spindle 136. The spindle 136 may carry a suitable grinding head 138 which is adapted to oppose the large end of the mantle. The saddle 134 may be otherwise free and tied to either one of the two outside saddles so as to move with it. For example, we show an interconnection 140 between the saddles 36' and 134 and it may take any suitable form. Accordingly, the auxiliary saddle will move with the saddle 36' but it might be tied to the other saddle 34'. The point is that during feed of either one of the saddles, the center saddle will be moved. The axis A of the center or auxiliary grinding head may be considered to be generally vertical and parallel to the rotary axis of the workpiece. This axis A does not necessarily lie in the same plane with the three axes X, Y and Z in Figure 3, and the axis A, while vertical, may be offset, preferably forward (relative to the machine in Figure 1), but it might be set back. In any event, the important point is that the auxiliary grinding head is fed with either one of the saddles and it opposes the large edge of the mantle.

During the operation of grinding the mantle casting, as set forth hereinabove, the fit and wear surfaces may be ground over a period of several hours. Toward the end of that time, we prefer to feed the spindle 136 down so that the grinding head 138 grinds off the upper large edge of the mantle to provide a flat control surface. This surface will be at right angles or perpendicular to the axis X which may be assumed to be the axis of the now accurately ground fit and wear surfaces.

The importance of this control surface on the finished mantle is as follows. The mantle fits on the gyratory head of a crusher and is held down on the somewhat conic head by what is commonly referred to as a retaining nut. For example, see Patent No. 2,684,208 for such an arrangement. In any event, the small opening or small end of the mantle is known as the throat, as at 142 in Figure 4. The edge of the casting at the throat is bevelled, as at 144, and this bevelled surface is normally referred to as the nut seat, meaning that the nut that holds the mantle down on the head comes down against this surface and seats against it. It is important that this nut seat 144 be finished, preferably by grinding, before the mantle is mounted on a head and the nut turned down.

By providing the control surface at the large end of the mantle, the nut seat may be accurately ground after the mantle is removed from the grinding setup of Figure 4 because the control seat will provide a plane, flat surface perpendicular to the trued axis of concentricity of the fit and wear surfaces. The control surface may be placed down on any smooth, flat surface, for example, a rotary table, and while the piece is rotated the nut seat can be accurately ground, and will be exact in concentricity to the previously ground fit and wear surfaces.

A grinding operation may require as much as four hours from start to finish. The down time between the end of one operation and the start of the next may take as much as forty-five minutes to an hour. This involves

removing the finished piece and mounting the next rough casting. To reduce this down time to a minimum, we provide a preassembling arrangement or method. For example, as shown in Figures 6 and 5, the normal table 5 is indicated generally at 12. To cover this table, we provide a flat plate 146 which conforms generally to the table, may be round, and is clamped or secured to the table in any suitable manner. In this setup, the plate 146 is what might be considered a cover plate for the normal table and it is clamped thereto and left in position. A second plate 148 is clamped on top of the cover plate 146. This second plate is removable, and suitable guides, bosses or other types of centering or piloting means are used so that the plate 148 always fits in the same position on the cover plate 146. As shown in Figure 5, the second plate has right angle, T-shaped notches 150 and 152 which divide the plate generally into quadrants and it may be provided with a suitable number of locating holes 154. These holes may be positioned in relation to the size of the standard castings to be ground. The arrangement shown could be varied and the particular locations are not important. The point is that a pattern of holes may be established, either in the notches to serve as stops for the jaws or clamps or outside of the notches or channels in different locations such as at 156. The holes or stops may be suitably marked so that the operator will instantly know which clamps to use in which holes for a particular casting.

The important point is that the top plate 148 may be set off to the side. For each machine, we might provide two, three, or four such plates. While one casting is being ground, the operator can be setting up another casting with its jaws, clamps, etc. on a second plate. When the grinding operation is completed on the first casting, it could be removed and the entire assembly of the casting clamped on a plate could be swung, by a suitable overhead crane or otherwise, onto the rotary table on top of the cover plate 146. We have found that we can reduce the down time as much as twenty-five percent by this pre-setup arrangement.

For the larger mantles and liners, we find that it is preferable to always individually mount the piece on the table and jaw and chuck it up, but for the smaller ones, they may be present, such as in Figures 5 and 6.

While we have stated that the axis of the third or center spindle is offset, either backward or forward, from the plane of the axes X, Y, and Z, it might be otherwise, and the invention should be understood to include a third spindle which is coplaner with the axes X, Y and Z. The particular size, design and style of adapter plate 146 and carrier plate 148, in Figures 5 and 6, is unimportant, and we have not gone into detail. The ground fit side and wear side on the workpiece, be it a mantle or liner, could be parallel or they could be otherwise. During an automatic operation, the operator's judgment is used to determine when sufficient material has been removed and a smooth ground surface of sufficient axial length has been provided. In Figure 4 we have shown the use of a third or center spindle to provide a control surface on the large end of a mantle generally perpendicular to the mantle axis or the axis of rotation, and this arrangement would not be used on a liner because the other end of a liner, the small end, does not have a nut seat.

This general type of grinding is only considered rough-cut work and it is not, in any sense, fine grinding. This grinding is only rough from the standpoint of surface finish. However, it must be accurate to produce straight concentric surfaces and true angles.

The use, operation and function of our invention are as follows:

The invention is concerned with a method of grinding wearing elements for use with gyratory crushers or the like. Such elements are termed mantles and liners and

are well-known and quite old. They are normally made of manganese steel which is very difficult if not impossible to machine. The rough cast workpiece, be it a mantle or liner, must be trued before it can be used in a crusher.

We provide a grinding method that insures concentricity, either for a mantle or liner. Our method is entirely automatic and foolproof.

We also provide a method of preparing a mantle by grinding so that the nut seat at the throat may be properly ground or otherwise prepared in proper concentricity with the axis of the mantle and the previously ground surfaces. In each case, the casting must have a wear side and a fit side.

The axes of the grinding heads, if extended, would intersect the upright rotary axis of the workpiece. The grinding is done simultaneously, both on the inner and outer surfaces, so that even if the casting is decidedly out of round, the ground surfaces will be accurate in concentricity.

The machine used has decided advantages because it is quite small, on a relative basis, and compact. The crossrail does not have to be unnecessarily long and the spindles are not too large and cumbersome. The mechanism shown has the distinct advantage that it will handle either mantles or liners without requiring excessive floor space. This is done by pivoting both of the spindles on the same side of their respective pivots, as shown in Figure 1, both on the right side rather than both being either inside or outside.

The preassembling setup shown and described may be used to reduce the down time of a machine as much as twenty-five percent.

The control panel, swingably mounted around the front of the machine, is of a particular advantage because it allows the operator to run a piece in without losing sight of or being unable to see or move to where he can see the roughing in operation of any other spindle.

While we have shown and described the preferred form

and several modifications of our invention, it should be understood that suitable additional modifications, changes, substitutions and alterations may be made without departing from the invention's fundamental theme. In

5 many places, we have only indicated the machine broadly without going into details because those details are of no importance to this invention, and it should be understood that any suitable mechanism may be used to carry out the functions, steps and operations described.

10 With these and other modifications in mind, we wish that the invention be unrestricted except as by the appended claim.

We claim:

A method of grinding frusto-conic manganese steel mantles to be used on the head of gyratory crushers and the like, including the steps of providing a generally frusto-conic truncated mantle casting, larger at one end than the other, and fully open through its central axis, positioning the mantle casting generally upright, large end up, in a grinding zone, rotating the casting at a generally uniform speed about its axis, simultaneously grinding concentric inner and outer frusto-conic surfaces adjacent the large end of the casting and also a flat control surface at the large end disposed generally at right angles to the axis of rotation, inverting the casting so that it rests on the flat control surface, and using the control surface as a reference while grinding an inwardly disposed somewhat conical throat surface at the small end of the casting to be engaged by the locking mechanism of the head of the crusher when fully seating the finished mantle in the crusher.
